UNITED STATES PATENT OFFICE

FREDERICK G. STREET, OF EAST ORANGE, NEW JERSEY, ASSIGNOR TO ANCIRA LOCK AND SEAL CORPORATION, OF NEW YORK, N. Y., A CORPORATION OF NEW YORK

SEAL

Application filed June 22, 1926. Serial No. 117,680.

The present invention relates to fastening devices or seals of the type more particularly used on containers to make it possible more readily to detect tampering with 5 the contents thereof, and has for an object to provide an improved device of this character.

The invention has been developed in connection with the production of a seal for 10 use on bank envelopes such as are used in the transmission of securities and, for convenience, this embodiment of the invention will be described as sufficiently illustrative of the principles involved. It will be understood however that the invention may be 15 variously applied, changes in the mechanical embodiment being made to suit the requirements of use.

Mail thieves and the like who make a practice 20 of removing from parcels entrusted to their care a part or all of the contents depend for success in concealing their thefts upon their ability quickly to open and re-seal parcels and yet leave no evidence that 25 the parcels have been tampered with. A postal employee would find it impossible, without detection, to remove securities from a registered bank envelope and substitute an equivalent weight of other papers unless 30 he could so reseal the parcel that it would not arouse the suspicion of the inspector or other employee to whom he might deliver it. But with practice thieves become expert in opening and resealing envelopes and the 35 problem of designing a seal that will prevent the opening of an envelope without conspicuous mutilation of the seal or of the envelope or which will make easy the detection of an envelope that has been opened 40 and resealed presents many difficulties. The difficulty of the problem is increased by the fact that the seal must necessarily be relatively inexpensive and must be so constructed that it can be quickly and easily sealed 45 by clerks having little mechanical skill.

The present invention provides a seal which in the preferred form is so constructed that after its parts have been connected it is practically impossible under the conditions of use to disconnect these parts with-

out mutilating one or both of them to such an extent as to leave obvious traces of the separation. The seal is also so constructed that it is practically impossible to detach one of the cooperating parts from an envelope or the like to which it has been applied and again attach it without seriously mutilating the paper or the fastener.

The nature and object of the invention will be better understood by reference to 60 the description of a particular illustrative embodiment thereof for the purpose of which description reference should be had to the accompanying drawing forming a part hereof and in which—

Figure 1 is a view of the back of an envelope having applied thereto two seals constructed in accordance with and embodying the principles of the invention.

Figure 2 is a view showing the two parts 70 of the seal disconnected but in position to be engaged.

Figure 3 is a central sectional view taken centrally of Fig. 2 on the line 3—3 thereof.

Figure 4 is a central sectional view similar to Fig. 3 but showing the parts of the fastener engaged.

Fig. 5 is a view of a partly folded blank showing the shape of the several parts of the female member.

Fig. 6 is a right side elevation of Fig. 5.

Figure 7 is a central sectional view of the female member completely formed and ready to be attached to an envelope but with the attaching prongs not bent.

Figure 8 is a sectional view taken on the line 8—8 of Fig. 3.

In the arrangement to be described for the purpose of illustrating the invention the closure flap 5 of an envelope 6 is secured 90 in closed relation by two similar fastener devices or seals 7.

The envelope is so formed and the fastening devices so arranged thereon that each possible opening of the envelope is controlled by one or more seals. As shown, each seal consists of cooperating male and female members 8 and 9 attachable respectively to the flap and body of the envelope and so constructed that when once they have 100

- been connected the engagement becomes permanent to effectively resist any effort to separate them. The side wings 10 of the envelope are of such length and so positioned relative to the end flap 11 that a wing and the flap which in fact constitute the body portion of an envelope are secured together by the female member of the fastener device.
- 5 10 In the particular construction shown the female member 9 consists of a blank which may be stamped from sheet metal folded to form a passage or socket 12 to receive the tongue 13 of the male member 8. One end 15 of the blank of the female member is folded in and back upon the body of the blank but in slightly spaced relation thereto to form a retaining element 14. This folded end of the blank is spaced sufficiently from the 20 body portion of the blank to form the socket 12 to receive the tongue 13, the extreme end of the retaining element being bent sufficiently toward the body of the blank to insure engagement with the cooperating hook 15 adjacent the end of the tongue 13. The character of the material is such that the retaining element 14 is sufficiently resili- 25 ent to yield permitting the hook 15 to pass behind the end thereof and then to spring into engaging position. The opposite end 30 17 of the blank is folded back upon the body of the blank but outside of the retaining element 14 to enclose said retaining element and provide an enclosure therefor.
- 35 40 The blank is cut as indicated at 18 to leave a tongue 19 which cut causes the opening 20 to be formed in one edge of the fastener when the end of the blank is folded inwardly and back upon itself to form the retaining element 14 as best indicated in Fig. 3. The side portions 22 of the blank are folded inwardly to complete the enclosure of the retaining element 14 and to prevent access thereto from the sides of the 45 device. The inner edges of the side portions are formed to provide prongs 23 which, when the fastener is applied to the paper, will extend through the paper and will be bent inwardly to secure the female member thereto. The central portion of 50 each side is extended to form a projection 24 which, in the finished fastener, is folded inwardly and against the back of the end 17, as indicated in Fig. 7 to hold said end 55 17 in closed relation. Prongs 25 are also formed at the lower edge of the female member as shown in Fig. 5 which prongs are arranged to extend through the paper and be folded to secure the fastener to the 60 paper. The fastener shown is thus provided with two prongs 23 on each side and with three prongs 25 at the lower edge of the fastener is shown in the drawing, these three prongs being shown in dotted lines in Fig. 65 2 to indicate the position thereof.

In order to interfere with the insertion of a tool into the female member through the opening 20 which receives the tongue 13 of the male member, the male member and the female member are provided with suitably arranged obstructions or projections. As shown the tongue 13 is formed on its inner face with an embossed projection 26 which bears against the inner wall of the passage 12 holding the tongue against the body of the socket member or wall 28, the inner folded end of the female member is formed with projections 29, 30. The projections 29 being of sufficient height to leave just sufficient space to permit the insertion of the tongue 13 against the wall 28 while the projections 30 are of sufficient height to engage the wall 28 and entirely close the passageway at each side of the tongue 13.

75 80 85 90 95 The tongue 13 is also provided with an inward projection 27. Preferably the tongue is perforated so that the projection 27 is in the form of a lip well adapted to engage and deflect any tool inserted along the inner face of the tongue 13. The projections 26 and 27 cooperate with the projections 29, 30 to substantially obstruct the passageway along the inner face of the tongue 13 when said tongue is in position in the female member.

In order that the fastener members may not be removed from the body or flap of the envelope by a bending of the prongs and again replaced and the prongs bent into holding position, all prongs are so scored that if bent backward and forward as is necessary in removing them from the envelope and again affixing the fastener they will be broken. The female member is also so scored along all lines of fold that in the event of any bending of the female member to open the same to permit access to the retaining element 14 an immediate breaking of the blank along said lines will occur.

100 105 110 115 120 In order to prevent the release of the tongue 13 from the retaining element 14 by means of a tool inserted in the opening 12 of the female member scores 33 are formed extending from the opening 12 across the body of the female member. Any bending of the female member adjacent the opening 12 will cause a tearing of the metal along the scores, which tearing will give a clear indication of the tampering and prevent restoring of the seal to its original condition.

125 The foregoing description of a particular embodiment is illustrative merely and is not intended as defining the limits of the invention.

I claim:

1. A seal of the character described comprising interengageable male and female members, the female member comprising a blank having one end slotted to provide an opening for the insertion of the male mem-

ber and folded inwardly and back upon the body of the blank to form a retaining element and its other end folded inwardly and back upon the body of the blank to enclose said retaining element and having its sides folded inwardly and cooperating with the said other end to completely enclose the said retaining element.

2. A seal as claimed in claim 1 wherein the retaining element is cut to provide a relatively narrow retaining tongue spaced from the sides of the fastener.

3. A seal as claimed in claim 1 wherein the female member is formed to provide a passage for the insertion of the tongue of the male member with projections extending into said passage to partially obstruct the same to prevent insertion of a tool beside said tongue.

4. A seal as claimed in claim 1 wherein the tongue and the female member are provided with cooperating obstructions arranged in staggered relation to prevent the insertion of a releasing tool beside the tongue.

5. A seal comprising interengageable sheet metal male and female members, the female member being formed of a blank folded to provide a flat rectangular closure with an opening at one side and at the other side a spring tongue entirely enclosed in said closure; the male member being formed with a tongue adapted to engage the spring tongue of the female member; said tongue and female member having projections arranged to lie in staggered relation when said members are interengaged to prevent the insertion of a releasing tool into the female member beside the tongue of the male member.

6. A seal of the character described comprising interengageable male and female members, the female member comprising a blank having one end folded inwardly and back upon the body of the blank to form a retaining element, a slot being formed at the fold to provide an opening to receive the tongue of the male member, said blank having its other end folded inwardly and back upon the body of the blank to enclose the retaining element, the sides of the blank being folded inwardly and cooperating with said other end to completely enclose said retaining element, said tongue of the male member being formed with a hook and a rib projecting from one side thereof, said hook being engageable with the retaining element and said rib being arranged to close said slot and to provide a stop to prevent the insertion of a releasing tool beside the tongue of the male member, substantially as described.

7. A seal of the character described comprising interengageable male and female members, the female member comprising a

blank having one end folded inwardly and back upon the body of the blank to form a retaining element, a slot being formed at the fold to provide an opening to receive the tongue of the male member, said blank having its other end folded inwardly and back upon the body of the blank to enclose the retaining element, the sides of the blank being folded inwardly and cooperating with said other end to completely enclose said retaining element, said tongue of the male member being formed with a hook projecting from one side thereof and engageable with said retaining element, said male member also being perforated at a point upwardly from said hook and in line therewith and having the edge of the perforation turned outwardly on the same side as said hook to provide a stop to prevent the insertion of a releasing tool beside said male member, substantially as described.

8. A seal of the character described comprising interengageable male and female members, the female member comprising a blank having one end folded inwardly and back upon the body of the blank to form a retaining element, a slot being formed at the fold to provide an opening to receive the tongue of the male member, said blank having its other end folded inwardly and back upon the body of the blank to enclose the retaining element, the sides of the blank being folded inwardly and cooperating with said other end to completely enclose said retaining element, said tongue of the male member being formed with a hook adjacent its free end engageable with said retaining element and with a deflecting projection and a rib in line with said hook and arranged to prevent the introduction of a releasing tool in said female member beside said tongue, and said female member being formed with inwardly extending projections between which said deflecting projection passes when the male and female members are connected, said inwardly extending projections being arranged to cooperate with said deflecting projection to prevent insertion of a releasing tool in said female member beside said male member.

9. A seal of the character described comprising a sheet metal female member providing a housing with an opening and a male member engageable therewith through said opening, said female member having scores extending from the opening in which said male member is inserted longitudinally along said male member to cause tearing of the female member in the event of distortion of said female member, substantially as described.

10. A seal of the character described comprising interengageable male and female members, the female member comprising a blank having a front wall and a portion

folded back from the front wall to form a back wall and a retaining element the retaining element being formed by slitting the back wall for a distance from one end 5 of the retaining element and the element being bent forward toward the front wall, the blank at one end being slitted and bent to form a slot for receiving said male member, the slot having a surrounding border of 10 uncut metal of the blank, and a retaining element formed on said male member co-operating with the retaining element of the female member.

11. A seal of the character set forth in 15 claim 10 in which the male member is formed with lateral shoulders closing the sides of the slot and positioned closely adjacent to the outer edge thereof when the parts are assembled together.

20 In testimony whereof, I have signed my name to this specification this 4th day of June, 1926.
